UNITED STATES PATENT OFFICE

ROBERT R. WEBB, OF LOS ANGELES, CALIFORNIA, ASSIGNOR TO CHARLES R. HADLEY COMPANY, OF LOS ANGELES, CALIFORNIA, A CORPORATION OF CALIFORNIA

LOOSE-LEAF BINDER

Application filed May 17, 1930. Serial No. 453,204.

This invention relates to loose-leaf binders and an important object of the invention is the improvement of the clamping means whereby one of the binder covers is held against movement away from the other cover.

5 This invention relates more particularly to that type of loose-leaf binder having posts on one cover member projecting through orifices in the other cover member, and an 10 other important object of the invention is improvement of the construction for clamping the cover member to the posts.

Another important object is simplicity and neatness of construction.

15 Other objects and advantages will appear in the subjoined detailed description.

The accompanying drawings illustrate the invention:

Figure 1 is a plan view of a loose-leaf 20 binder constructed in accordance with the provisions of this invention.

Fig. 2 is a front elevation of Fig. 1.

Fig. 3 is an enlarged fragmental vertical 25 section on the line indicated by 3—3, Fig. 1. Fig. 4 is a horizontal section on the line indicated by 4—4, Fig. 3.

Referring to the drawings, there are provided cover members 6, 7. The cover member 6 comprises a movable section 8 hinged at 9 to a section 10 that constitutes a clamping bar. The cover member 7 comprises a movable section 11 hinged at 12 to another section 13 that constitutes a second clamping bar.

Fixed in the clamping bar 10 are posts 14. 35 The posts 14 may be secured in any suitable manner to the bar 10 and, in this instance, said posts have portions 15 of reduced diameter threaded into the bar 10.

The posts 14 project through circular 40 orifices 16 in the clamping bar 13. In this instance, the walls of the orifices 16 are formed by metal bushings 17 which are accommodated in holes 18 in a block 19. The blocks 19 close the ends of a rectangular 45 tube 20 that constitute the main body of the clamping bar 13. Each bushing 17 has a shoulder 21 that engages the inner face of the tube 20 and the adjacent end 22 of said bushing is crimped down upon the outer face 50 of the said tube 20. The other end of the

bushing 17 projects slightly outside of the tube 20 and is crimped over a cover plate 23 that excludes dirt from the bore of the bushing.

The cover plates 23 are provided with central orifices 24 to accommodate sleeves 25 through which the posts 14 project. The inside diameter of the sleeves 25 is sufficiently greater than the diameter of the posts 14 to permit of the sleeves easily slipping on and off of the posts.

Each of the sleeves 25 is normally held inwardly by a coil spring 26 that surrounds the sleeve between its associated cover plate 23 and an external shoulder 27 on the sleeve.

Each sleeve 25 carries a number of friction members 28 which, in this instance, are in the form of balls that are accommodated in radial orifices 29 in the sleeve 25.

The wall of that portion of the sleeve that projects into the orifice 16 is of less thickness than the diameter of the members 28 and the outer faces of the members 28 are adapted to frictionally engage the wall 30 of the orifice 16. This wall 30 is tapered or of conical shape, the smaller end thereof being toward the clamping bar 10. When the members 28 are at the lower portion of the orifice 16 and in contact with the wall 30, the inner faces of the members 28 are in contact with the posts 14 and, accordingly, the bar 13 is clamped by the members 28 to the posts 14, each coil spring 26 yieldingly holding its associated sleeve with the members 28 in the smaller end of the orifice 16. To release 50 the post from the pressure of the members, it is necessary to retract the sleeve against the pressure of the spring. To facilitate retraction of the sleeves, the outer ends of said sleeves are provided with flanges 31. The flanges 31 are sufficiently removed from the cover plates 23 to permit the operators' first and second fingers to be positioned beneath the flanges 31 so as to readily retract the sleeves.

Of course the outside diameter of that portion of each sleeve that projects into the orifice 16 is materially less than the diameter of the smaller end of said orifice so that only the members 28 will engage the wall 30.

The invention described above operates as follows: To insert loose leaves in or remove them from the binder, it is necessary to remove the cover member 7 and this is done by the operator simultaneously retracting the sleeves 25. As he pulls upwardly on said sleeves, the weight of the cover member 7 tends to hold it stationary and, accordingly, there is sufficient relative movement between the sleeve and cover member to compress the springs and move the members 28 into the larger ends of the orifices 16, thereby relieving the inward wedging effect of the wall 30 upon said shoes. Continued upward pull on the sleeves, by the operator, will then lift the cover member 7 and said cover member will be entirely removed from the posts. The desired number of loose leaves will then be removed from the posts or placed thereon and the cover member 7 will then be replaced on the posts, the weight of said cover member causing it to descend on the posts until it lies against the upper loose-leaf. The members 28 automatically clamp against the posts at the lowest point reached by said sleeves, thus firmly holding the clamping bars 10, 13 against movement away from one another until the sleeves are again retracted by the operator.

30 It will be seen from the foregoing that the construction is quite simple and yet is very effective to accomplish the purpose for which it is intended.

I claim:

35 A loose-leaf binder comprising cover members, a bushing fixed in one of the cover members and having a tapered bore, a sleeve projecting through the bushing and provided with a shoulder, a cover plate on the bushing 40 at the larger end of the bore of said bushing fitting around the sleeve, a post fixed in the other cover member and projecting through the sleeve, a spring surrounding the sleeve between the inner face of the cover plate and the shoulder, and a friction member carried 45 by the sleeve engageable with the post and with the inner face of the bushing, said friction member being positioned inwardly from the shoulder.

50 Signed at Los Angeles, California, this 7th day of May, 1930.

ROBERT R. WEBB.
